CLAIM

The ornamental design for a juice extractor body as shown and described.

DESCRIPTION

FIG. 1 is a top, front perspective view of a juice extractor body;

FIG. 2 is a bottom, front perspective view thereof;

FIG. 3 is a front elevational view thereof;

FIG. 4 is a rear elevational view thereof;

FIG. 5 is a top plan view thereof;

FIG. 6 is a bottom plan view thereof; and,

FIG. 7 is a left side elevational view thereof.

The broken lines are shown for the purpose of illustrating environmental subject matter of an exemplary vertical juicer forming no part of the claimed design. The drawings include stipple shading to show contrast of materials.

1 Claim, 6 Drawing Sheets
